UNITED STATES PATENT OFFICE

DOUGLAS L. FELTHAM, OF TOLEDO, OHIO

INSPECTION AND CLEAN-OUT DOOR

Application filed October 10, 1928. Serial No. 311,535.

This invention relates to an inspection and clean out door especially adapted for use on steam boilers and the like. Heretofore, in connection with such doors, whether of the 5 hinged or sliding type, it has been necessary, each time the door is closed, to seal the crack between the door and the frame with some kind of cement compound, in order to obtain a tight joint.

10 It is primarily with the object of saving time and expense in connection with the inspection of boilers, therefore, that the present invention has been perfected. With this end in view, the door and the frame are cast with 15 raised peripheral portions adapted to be ground to form coengaging surfaces which fit closely without the use of cement. The door is composed of comparatively thin light metal, dished to form an outturned peripheral 20 reinforcing flange, with wedge-shaped portions adapted to engage anti-friction rollers carried by the frame, to secure the door tightly against its seat. Consequently the 25 door is light and strong, may be readily opened or closed, and is not easily warped by heat when in closed position.

The objects and advantages of the invention will be more particularly explained in connection with the accompanying drawings, 30 which illustrate in detail one embodiment of the same.

In the drawings:—

Figure 1 is a front elevation of the door and frame, the door being in closed position.

35 Fig. 2 is a sectional view taken on the line 2—2 of Fig. 1.

Fig. 3 is a sectional view taken on the line 3—3 of Fig. 1.

40 In the construction to which the invention relates, the door frame 5 is bolted or otherwise secured to the wall 7 of the boiler and is formed with an inturned flange 6 which defines the door opening. The door 8 is preferably cast from aluminum or other suitable metal and is dished to form a peripheral outturned flange 9, so that the door may be comparatively thin and light, and at the same time strong and not easily warped.

50 The door is adapted to open or close by a vertical sliding movement and the frame 5

is formed with vertical flanges 10 between which the door is guided. Each flange 10 has a central extended portion 11 in which a bolt or other bearing member 12 is mounted for supporting an anti-friction roller 13, 55 which overhangs the edge of the door and is adapted to engage the inclined portion of the flange 9.

In casting the frame and door, the coengaging portions are slightly thickened, as 60 shown at 15 and 16, so that they may be subsequently machined to form a tight joint without the use of any cement. When the door is closed it is free to move downwardly until it is wedged tightly against its seat. For convenience in manipulating the door, 65 handles 17 may be cast into the same. In opening the door, its lower edge may be tapped to loosen it.

70 Thus it will be seen that the door and frame may be manufactured at a moderate cost, will be strong and durable, and will save a great deal of time and expense when the boiler is inspected or cleaned. While I have illustrated and described in detail one specific embodiment of the invention, it will be readily seen that the same may be considerably modified without departing from the scope of the invention as claimed.

75 What I claim is:

1. The combination with a metallic door frame formed with a seat having a plane surface circumscribing the door opening, of a door slidable into closed position and having a plane surface engageable with the surface of said seat to constitute a tight closure, flanges formed on the outer face of the door near opposite sides thereof and having inclined faces, and anti-friction rollers mounted 85 on the sides of said frame in position to engage said inclined faces, as the door is closed, to wedge the door against said seat.

90 2. The combination with a metallic door frame formed with a seat having a plane surface circumscribing the door opening, of a door slidable into closed position and having a plane surface engageable with the surface of said seat to constitute a tight closure, said door being dished inwardly to form an outturned continuous reinforcing rim, the oppo- 95 100

site side portions of said rim having inclined faces, and anti-friction rollers mounted on the sides of said frame in position to engage said inclined faces, as the door is closed, to wedge the door against said seat.

3. The combination with a metallic door frame formed with a seat having a plane surface circumscribing the door opening, of a door slideable into closed position and having 10 a plane surface engageable with the surface of said seat to constitute a tight closure, the sides of said frame being formed with vertical guide flanges between which the door is guided, anti-friction rollers mounted on said 15 flanges and overhanging the side edges of the door, and vertical flanges formed on the outer face of the door near the sides thereof and having inclined faces engageable beneath said rollers, as the door is closed, to wedge the door 20 against said seat.

4. The combination with a metallic door frame formed with a seat having a plane surface circumscribing the door opening, of a door slideable into closed position and having 25 a plane surface engageable with the surface of said seat to constitute a tight closure, the sides of said frame being formed with vertical guide flanges between which the door is guided, and anti-friction rollers mounted on 30 said flanges and overhanging the side edges of the door, said door being dished inwardly to form an outwardly disposed continuous reinforcing rim, the opposed vertical side portions of said rim having inclined faces engageable beneath said rollers, as the door is 35 closed, to wedge the door against said seat.

In testimony whereof I have hereunto signed my name to this specification.

DOUGLAS L. FELTHAM.
